NICHOLAS L. COYLE, OF WOODHAVEN, AND FRANK DI IANNI, OF BROOKLYN, NEW YORK, ASSIGNORS TO AMERICAN MACHINE & FOUNDRY COMPANY, A CORPORATION OF NEW JERSEY

REVERSIBLE CIGARETTE-ROD SEALER

Application filed February 18, 1930. Serial No. 429,313.

This invention relates to cigarette rod sealers. These sealers are provided with a sealing surface extending along the cigarette rod and engaging the same to press together and smooth the freshly pasted overlapping edges of the paper strip. Excess paste accumulates on the sealing surface which must be periodically removed to prevent the excess from smudging the rod. With prior sealers it has been necessary to stop production while the sealer was being cleaned.

The object of this invention is to avoid this loss of production by providing sealing mechanism which can be cleaned without holding up the operation of the machine. To this end it is an object of the invention to construct a rod sealer which has separated sealing surfaces so mounted that one may be cleaned while another is in action and vice versa.

With these and other objects not specifically mentioned in view the invention consists in certain constructions and combinations which will be hereinafter fully described and then specifically set forth in the claims hereunto appended.

In the accompanying drawings, which form a part of this specification and in which like characters of reference include the same or like parts, Fig. 1 is a plan view partly broken away of a sealer constructed in accordance with the invention; Fig. 2 is a side elevation partly in section of the device shown in Fig. 1 and Fig. 3 is a sectional end elevation 35 on the line 3—3 of Fig. 2.

In carrying the invention into effect there is provided a rotatable support extending along a traveling cigarette rod, together with two supported sealing bars carried by said support with one engaging the seam of the rod and with the other in position to be cleaned while the engaged bar is in action. In the best constructions these bars are located at diametrically opposite positions on said support.

Referring to the drawings, a bracket 10 attached to the frame of the cigarette machine carries a stud 11 on which is pivoted a forked arm 12 having aligned bores in which 50 is rotatably mounted a tubular support 13

extending along the cigarette rod C with its axis parallel to the rod. A knob 14 on the end of the tube facilitates turning the tube to reverse the sealing surfaces supported thereon as described below.

Two spaced sealing bars 16 are secured in slots of a frame 15 fixed to the tube with the sealing surface of the bars at diametrically opposite positions with respect to the axis of the tube 13. A heating element 17 within the tube serves to heat the sealing bars. A guard 19 is pivoted at 18 on the arm 12. Conduction of heat from the tube to the arm 12 is retarded by heat insulating bushings 20 and 21 in the bores thereof.

The supporting tube 13 is held with the bars in either one of their two positions with the bar which is in operating position properly located relative to the rod by means of a ball 22 in the arm 12 pressed by a spring 23 and nut 24 into either one of two diametrically opposite notches in the tube. A set screw 25 in the arm 12 regulates the sealing pressure.

The rod C carried in the direction of the arrow in Fig. 2 by the usual driving tape 26, issues from the rod former 27, 28 where paste is applied and the rod closed, into contact with one of the bars 16, which presses and smooths the seam and dries the paste. When paste accumulates thereon the knob 14 may be quickly turned to a position in which the ball 22 snaps into the opposite notch. The guard 19 can then be lifted and the upper bar cleaned at the operator's convenience, during the operation of the machine.

What is claimed is:

1. The combination with a rotatable support extending along a traveling cigarette rod, of two separated sealing bars carried by said support with one engaging the seam of the rod and with the other in position to be cleaned while the engaged bar is in action.

2. The combination with a rotatable support extending along a traveling cigarette rod, of two separated sealing bars carried by said support with one engaging the seam of the rod and with the other in position to be cleaned while the engaged bar is in action, said bars being located in diametrically opposite positions on said support.

3. The combination with a rotatable support extending along a traveling cigarette rod, of two separated sealing bars carried by said support with one engaging the seam of the rod and with the other in position to be cleaned while the engaged bar is in action, and means for heating said support and said bars.
4. The combination with a rotatable support extending along a traveling cigarette rod, of two separated sealing bars carried by said support with one engaging the seam of the rod and with the other in position to be cleaned while the engaged bar is in action, and a frame carrying said support and bars and movable in and out of operative position.
5. The combination with a frame, of a rotatable support thereon, a plurality of spaced sealing elements secured on said support in position for movement therewith into operative engagement with the rod, and means for holding said support in any one of a plurality of predetermined positions in each of which one of said surfaces engages the rod and another is in position to be cleaned.
6. The combination with a frame, of a rotatable support thereon, a plurality of spaced sealing elements secured on said support in position for movement therewith into operative engagement with the rod, and means for holding said support in any one of a plurality of predetermined positions in each of which one of said surfaces engages the rod and another is in position to be cleaned, said means comprising a spring pressed ball and a co-operating notched surface.
7. The combination with a frame, of a rotatable support thereon, a plurality of spaced sealing elements secured on said support in position for movement therewith into operative engagement with the rod, and means for holding said support in any one of a plurality of predetermined positions in each of which one of said surfaces engages the rod and another is in position to be cleaned, said support comprising a cylindrical element axially rotatable in said frame and a slotted holder secured about said cylindrical element, said sealing elements being secured in the slots of said holder.
8. The combination with a frame, of a rotatable support thereon, a plurality of spaced sealing elements secured on said support in position for movement therewith into operative engagement with the rod, and means for holding said support in any one of a plurality of predetermined positions in each of which one of said surfaces engages the rod and another is in position to be cleaned, said support including a tube journaled in said frame, and a heating element in said tube.

In testimony whereof, we have signed our names to this specification.

NICHOLAS L. COYLE.
FRANK DI IANNI.
